SHARPENING DEVICE

Albert P. Komow, Great Neck, N. Y., assignor to
 U. S. Cloth Cutting Machine Co., New York,
 N. Y., a corporation of New York

Application February 16, 1950, Serial No. 144,430

9 Claims. (Cl. 30—139)

1

My invention relates to a new and improved sharpening device for a cloth-cutting machine of the reciprocating straight-knife type.

One of the objects of the invention is to provide a grinder mechanism which is normally held in an upper, inoperative position, and which, upon actuating a suitable control member, will be automatically moved vertically to a lower operative position, from which it is raised automatically while it sharpens the knife.

Another object of the invention is the provision of a grinder mechanism of the character described, in which the presser-foot rod is adapted to be moved automatically to its bottommost position in which the presser-foot is clear of the knife, simultaneously with the start of the downward movement of the grinder mechanism, and in which said presser-foot rod is automatically raised to an uppermost position with the grinder mechanism.

Still another object of the invention is to provide sharpening means in which the grinder stones contact the knife only during the upward movement of the grinder mechanism, thus giving longer life to the knife.

A further object of the invention is the provision of sharpening means of the character described, in which the grinder mechanism may be manually adjusted to compensate for wear of the knife and also to obtain various width bevels on the knife.

A still further object of the invention is the provision of a presser foot which is transparent, so that the work can be observed by the operator during the cutting operation.

These and additional objects of my invention are set forth in the following description and drawings which illustrate a preferred embodiment thereof, it being understood that the above statement of the objects of my invention is intended generally to explain the same without limiting it in any manner.

Fig. 1 is a side elevation of the cloth cutting machine embodying the improved device, with portions thereof being broken away along line 1—1 of Fig. 3 to more clearly reveal certain interior construction. In this view the sharpening assembly is shown during its downward travel intermediate its top and bottom positions;

Fig. 2 is a fragmentary front elevation with portions of the machine being shown in section. In this view the sharpening assembly is shown in its uppermost position which is the normal cutting position of the machine;

Fig. 3 is a fragmentary front elevation partially

in section taken along line 3—3 of Fig. 1. This view is similar to that of Fig. 2, except that the grinding mechanism is in the course of its downward travel;

5 Fig. 4 is a front elevation similar to Fig. 3, but showing the grinder mechanism as it arrives at its lowermost position. In this view the grinder assembly is shown in section as taken along line 4—4 of Fig. 9;

10 Fig. 5 is a front elevation similar to Fig. 4, but showing the grinder assembly as it begins its upward travel;

Fig. 6 is a horizontal sectional view taken along line 6—6 of Fig. 7. The position of the machine 15 parts in this view corresponds to that of Fig. 1;

15 Fig. 7 is a rear elevational view of the machine in which the position of its parts corresponds to that shown in Fig. 4; and the uppermost position of the grinder assembly is shown in broken line;

20 Fig. 8 is a partial rear elevation, similar to Fig. 7, but showing the grinder assembly in its uppermost position which corresponds to the position of Fig. 2;

Fig. 9 is a bottom plan view of the grinder assembly of the machine with the grinders shown in their spread or inoperative position; and

25 Fig. 10 is a vertical sectional view of the grinder assembly, taken along line 10—10 of Fig. 9.

Certain parts of the cloth cutting machine may 30 be of any standard or conventional construction.

Referring to Fig. 1, the machine has a base 10, a handle 11, fixed to the frame of the machine, and a motor casing 12. The motor housed within the casing is of the usual type and its construction is, therefore, not shown in detail. The machine has a longitudinal standard 14, in which a longitudinal knife 15 is guided and mounted for longitudinal or vertical reciprocating movement. The mechanism for longitudinally reciprocating the knife 15 in a selected longitudinal path is conventional and well known; therefore, reference will hereafter be made thereto only insofar as its operation is related to that of the improved grinding mechanism. The standard 14 is part of the frame.

45 The machine also has a lateral presser foot 16. Said presser foot is fixed at one end to the bottom of a retaining arm 22, by means of rivets 21 or other means of attachment. The retaining arm 22 is secured to the lower end of a longitudinal presser-foot rod 18, by means of screws 17. The presser foot 16 is forked at its free end, and the edge of knife 15 is located in said fork, so that presser foot 16 acts as a guard. The longitudinal presser-foot rod 18 has the usual

50 55

vertical series of horizontal and laterally disposed teeth 19, and has at its upper end a finger hold 20 by means of which the rod 18 may be manually adjusted in vertical position at any desired height.

Presser foot 16 is preferably made of a thick transparent plastic such as Lucite or the like so that it is possible to see the work being done while the machine is being used in its cutting operation. Said transparent presser foot 16 may have a longitudinal guide line (not shown) which is parallelly aligned with the longitudinal axis of the machine base, so that the operator of the machine may insure a straight cut in the cloth.

In general the machine has grinding mechanism which is mounted for longitudinal or vertical movement relative to the standard 14 and knife 15. During normal cutting operation, this grinding mechanism is located at the upper end of the knife in an inoperative position in which its grinders are out of contact with the knife. When a suitable lever is actuated, however, the grinding mechanism is automatically brought to the bottom of the knife, the grinders are automatically brought into contact with the knife, and the grinding mechanism is automatically raised to its original position. During this raising operation, the grinders sharpen the knife. After the grinding mechanism is brought to its original raised position at the upper end of the knife, it is automatically held in this position until the lever is again actuated.

In Fig. 7, the shaft 24 of the electric motor in casing 12 is shown. Shaft 24 is keyed or otherwise suitably rigidly connected to disc 25. A pin 26 is connected off center to the disc 25, and the head 27 of connecting rod 28 is turnably mounted upon the pin 26. The lower end of the connecting rod 28 is pivotally connected to the top of the usual knife-support 15a. This connection is not shown as it is well known. The annular periphery of the disc 25 is cut in order to provide a worm gear 29. This worm 29 can mesh with a worm wheel 30, whose hub 31 is releasably fixed to the turnable and vertical shaft 32. This shaft 32 is rotatably mounted in a special bracket or housing H. The hub 33 of a bevel gear 34 is also fixed to the shaft 32, so that the worm wheel 30 and the bevel gear 34 turn in unison. The bevel gear 34 meshes with either of two companion bevel gears 35 and 36 whose respective hubs 37 and 38 are rigidly connected to opposite ends of a horizontal shaft 39, as is shown in Fig. 6. The companion bevel gears 35 and 36 are horizontally or transversely aligned with each other, and face each other. The outer end of the hub 38 of inner bevel gear 36 is secured to a pinion 40 which meshes with a vertically-movable rack 41. The shaft 39 turns in a bearing 42 which is part of the bracket or housing H, and is transversely slideable in said bearing 42 so that either of the companion bevel gears 35 or 36 may be alternately brought into operative engagement with the bevel gear 34. The bevel gears 35 and 36, the horizontal shaft 39, and the pinion 40 turn in unison. A compression spring 43 is mounted on a pin 44 whose head is seated in a recess 45 of the machine frame. Said spring 43 extends into a bore 46 in the center of pinion 40 and normally urges the shaft 39 to a position in which the inner bevel gear 36 meshes with the bevel gear 34, and the bevel gear 35 is out of engagement with said bevel gear 34.

As shown in Fig. 6, the hub 37 of bevel gear

35 is stud shaped, having a peripheral groove 37a. A retaining arm 47 is mounted adjacent said hub 37, said retaining arm 47 having an arcuate recess which fits within the peripheral groove 37a of hub 37. Said retaining arm 47 is mounted on a block-like lever 48 by means of screws 49. The lever 48, as shown in Figs. 2-5, is pivotally mounted at one end on the machine frame by means of a screw 50. A tension spring 51, which is attached at one end to the lever 48 by an elongated screw 48a and at the other end to the frame of the machine, urges the lever 48 to its normal position shown in Fig. 3 in which the retaining arm 47 is disposed in a vertical position. If, at this time, the inner bevel gear 36 is in contact with bevel gear 34, as shown in Figs. 1, 3 and 6, the arcuate groove of retaining arm 47 is located within the peripheral groove 37a of hub 37, thus locking the inner bevel gear 36 and the bevel gear 34 in their meshed relationship. If, on the other hand, the outer bevel gear 35 is in operative engagement with the bevel gear 34, as shown in Fig. 5, the retaining arm 47 is located in front of and abuts the front face of the hub 37, locking said outer bevel gear 35 in its operative position.

The rear end of a transverse bar 52 is slidably housed in a vertical slot 53 of the machine frame. The front end of said transverse bar 52 is rigidly connected to a vertical rod or shaft 54 which is mounted for longitudinal sliding movement in a bearing of the machine frame. The vertical rod 54 thus guides the transverse bar 52 in the vertical movement of said transverse bar 52. A flat spring 55 is secured at its top end to the outer face of the transverse bar 52 by means of screws 56. This flat spring 55 extends vertically downwardly from the transverse bar 52 and has a cam-shaped free bottom end 57 which abuts the hub 37 of outer bevel gear 35. Spring 55 is preferably made of a strong metal which is semi-flexible such as a thin sheet of spring steel. As shown in Fig. 1, the spring 55 is made of a double thickness of this sheet metal. When the retaining arm 47 is pivoted out of contact with the hub 37 of bevel gear 35, as shown in Fig. 4, and the transverse bar 52 is moved downwardly, the cam-shaped free bottom end 57 rides over the face of hub 37 and presses the outer bevel gear 35 into meshed engagement with the bevel gear 34, against tension of the compression spring 43.

Rack 41 is moved vertically in either an upwardly or downwardly direction by pinion 40, depending upon which of the bevel gears 35 or 36 is in meshed engagement with the bevel gear 34.

The bracket H is mounted turnably on the horizontal shaft 39, as shown in Fig. 6, so that said bracket H has a limited transverse turning movement relative to the frame of the machine. The rack 41 is guided in a suitable bore of the machine frame, independently of the bracket H, so that the movement of the rack 41 is always vertical.

A grinder bracket 58 is secured to the lower end of the rack 41 by a screw 59 or by any other suitable means. One end of a transverse blade spring 60 is secured to the bracket 58, preferably by screws 61. The other end of the blade spring 60 is secured to a block 62 and to a transverse bar 63, by means of screws 64, as shown in Fig. 9. This bar 63 is of rectangular cross-section as shown in Fig. 10.

A pair of slides 65 and 66 are mounted for sliding movement on said bar 63. Slides 65 and 66 have respective angular faces which slidably

interfit with bar 63, so that slides 65 and 66 are transversely slidable relative to bar 63.

Each slide 65 and 66 bear respective rotatable grinders 67 and 68 which are of the usual disc type. The shafts of grinders 67 and 68 are perpendicular to each other.

As shown in Fig. 4, the ends of transverse bar 63 are provided with respective recesses or slots 69 and 70. As shown in Figs. 4 and 9, the upper slide 65 is provided with a recess or slot 71, at its end which is opposed to the respective grinder 67. The lower slide 66 has a recess or slot 72 at its end adjacent its respective grinder 68.

The shank of a vertical bolt 73 extends through slot 69 of bar 63 and the vertically alined slots 71 of upper slide 65. Said shank of bolt 73 extends through a bore of lower slide 66, and is held securely in place by a nut 74.

The shank of another vertical bolt 75 extends through slot 70 of bar 63 and the vertically alined slot 72 of lower slide 66. Said vertical shank of bolt 75 is held in place by a nut 76.

The slides 65 and 66 are thus slidable relative to bar 63, in a transverse direction which is parallel to the axis of bar 63.

The superposed outer vertical faces of the slides 65 and 66 are provided with respective lateral pins 77 and 78, which are fixed respectively to said slides. One end of a tension spring 79 is connected to pin 78. The intermediate part of tension spring 79 passes movably around pin 77. The leg of tension spring which interconnects pins 77 and 78, thus urges said slides 65 and 66 to move relative to each other in respective opposed transverse directions, and thus urges the respective grinders 67 and 68 to move transversely towards each other and towards the edge-faces of knife 15.

The relative transverse movement of slides 65 and 66, in respective opposed directions, is controlled by a control arm 80, which is turnably connected by a pivot pin 81 to bracket 58. This control cam 80 has a lower end of tapered shape, which has a cam face 80b which contacts with pin 77. Said tapered part of control cam 80 also has a cam face 80c which abuts pin 78. The top end of cam face 80c terminates in an arcuate recess 80d into which the pin 78 may enter to releasably lock the control cam 80 in its downwardly turned position shown in Fig. 2. The cam face 80b terminates in a lower transverse extension 80e which acts as a stop to prevent the control cam 80 from being turned upwardly out of contact with the pin 77. When control cam 80 is turned upwardly, the slides 65 and 66 can be moved relative to each other by tension of spring 79, so as to move their grinders 67 and 68 towards each other. When the control cam 80 is turned downwardly, the transverse spacing between the grinders 67 and 68 is increased. The top edge of control cam 80 is provided with a horizontal extension-arm 80a, the outer end of which is downwardly turned.

One end of tension spring 79 is connected to a pin 82, which is fixed to an adjustment plate 83. Adjustment plate 83 is pivoted at its upper end to control cam 80 by pivot pin 83a. By turning this adjustment plate 83 relative to control cam 80, the tension of spring 79 can be adjusted. Adjustment plate 83 is provided with three holes or recesses C, M and S. The control cam 80 is provided with a lug or projection 84 which is located directly below the pivot of adjustment plate 83 and is positioned to extend within any one of the holes C, M or S when the

adjustment plate 83 is turned, thus locking the adjustment plate 83 in any one of three selected positions relative to control cam 80. When lug 84 is located within the hole or recess S, the spring 79 is under minimum tension, which corresponds to the grinding of the edge of the knife 15 to maximum sharpness or finish. When lug 84 is located within the hole or recess M (as shown in the drawings), the tension of spring 79 is greater, and the grinders 67 and 68 produce a medium edge-finish on knife 15. When lug 84 is located within the hole or recess C, the spring 79 is under maximum tension, and the grinders 67 and 68 are urged towards each other with maximum force, and a coarse grinding is produced on knife blade 15.

Fig. 10 shows a hollow adjusting screw 85 which extends laterally through a tapped bore of bracket 58. The end of this hollow screw 20 85 has an enlarged terminal sleeve 85a which abuts the bar 63, so that bar 63 can be adjusted laterally relative to bracket 58, since the blade spring 60 provides a bendable and resilient connection between bracket 58 and bar 63. This 25 lateral adjustment of bar 63 relative to bracket 58 makes it possible to adjust the grinders 67 and 68 laterally relative to standard 14, in order to allow for knives 15 of different widths. Also, as a knife 15 becomes worn, it is possible to adjust bar 63 and its sliders 65 and 66, closer towards standard 14.

As is clearly shown in Figs. 7 and 10, the hollow screw 85 is split longitudinally. When bar 63 has been adjusted by screw 85, said bar 63 is 30 locked in adjusted position by a pin 86, whose shank has a threaded end which engages the thread of a tapped bore 87 of bar 63. The pin 86 has a head 86a which has a conical base 86b. When said pin 86 is screwed inwardly, the conical base 86b enters a correspondingly-shaped recess in the head of the hollow adjusting screw 85, wedging said split screw 85 apart, and locking it in its adjusted position.

Means are provided for automatically turning 45 the control cam 80 upwardly, so as to move the grinders 67 and 68 automatically toward each other into operative grinding positions when the bracket 58 is moved to its bottom position of Figs. 4 and 7. As shown in Fig. 7 the presser-foot rod 18 has a bottom lateral projection or extension 88. When bracket 58 is moved to its bottom position, the downwardly-turned end of the transverse extension arm 80a of control cam 80 strikes the top of lateral projection 88, causing 50 said control cam 80 to snap upwardly so that the grinders 67 and 68 are moved towards each other to contact with the faces of the edge of knife 15.

The head 89 of a screw protrudes below the bottom surface of the machine frame. When the bracket 58 is moved to its top position of Fig. 2, the extension arm 80a of control cam 80 strikes this screw-head 89 and is turned downwardly, just before bracket 58 reaches its top position, thus transversely separating grinders 67 and 68 from the transversely opposed faces of the edge of knife 15. The pin 78 enters the recess 80d of the control cam 80, thus releasably locking said control cam 80 in its downwardly-turned position, and holding grinders 67 and 68 transversely separated from knife 15.

As shown in Fig. 2, the housing H is provided with a lateral extension which has a vertical recess 90. As shown in Fig. 1, a latch 91 is pivotally connected to the frame of the machine by a horizontal transverse pivot pin 92, so that latch

91 turns in a lateral plane. A vertical compression spring 93, which is located in a vertical recess of the frame of the machine, biases the latch 91, to urge its latch finger 94 to enter recess 90 and thus hold housing H in the operating position of Fig. 3 in which worm gear 29 meshes with worm wheel 30. The latch 91 has a rectangular slot 95 located in the rear face thereof.

As shown in Figs. 1 and 4, a transverse screw 96 is fixed to the lower end of rack 41. When rack 41 is raised to the position of Fig. 2, screw 96 strikes the upper face of slot 95 in latch 91, thus turning latch 91 against the force of spring 93 to release housing H.

A transverse rod 97 is turnably mounted in a bearing of the machine frame, as shown in Fig. 6. An enlarged sleeve 97a is removably secured to the outer end of rod 97. A lever 98 is also fixed to said transverse rod 97 intermediate the ends thereof, said lever 98 depending from said rod 97. The end of a block 99 is secured to the rear end of the rod 97. An actuating lever 100 is connected to said block 99. Said actuating lever 100 has a bracket-shaped end 101 which is pivoted to said block 99 by a pivot pin or screw 102, so that said lever 100 is horizontally pivotable in a rearwardly direction, independently of the block 99, as shown by the broken line representation of Fig. 6. A compression spring 103, which is seated in a bore 104 of block 99, bears against the end of actuating lever 100 and normally urges said lever 100 to its normal position shown in Fig. 6, in which said lever 100 is held inwardly adjacent the machine frame.

A torsion spring 105 encompasses that portion of the transverse rod 97 between the lever 98 and the sleeve 97a. One end of this torsion spring 105 is secured to the sleeve 97a. The other end of said spring 105 is secured to the frame of the machine. This spring 105 normally urges the lever 100 to its downwardly-tilted position shown in Fig. 7. In this position, the lower end of depending lever 98 abuts the enlarged head of a pin 107 whose shaft has a threaded end which is adjustably secured to the housing H. When the lever 100 is raised from its normal downwardly-tilted position against the tension of coil spring 105, it causes the bar 99, the rod 97, the lever 98, and the sleeve 97a, to turn in unison. The depending lever 98 is thus turned from the position of Figs. 3, 4 and 5, in which its lower end abuts the head of pin 107, to the position of Fig. 2 in which the lower end of lever 98 is moved toward the housing H. The lower end of the depending lever 98 is provided with a transverse bore 108 in which one end of a compression spring 109 is seated. The housing H is also provided with a similar transverse bore 110 which is transversely aligned with bore 108 of lever 98. The other end of compression spring 109 is seated in said bore 110. When lever 98 is turned toward housing H, it bears against and increases the tension of compression spring 109, causing said spring 109 to urge the housing H to turn about its pivot, the horizontal shaft 39, until the worm wheel 30 is brought out of meshed relationship with the worm gear 29, as shown in Fig. 2. The housing H may be so pivoted or turned when the latch finger 94 is removed from its corresponding recess 90 in housing H.

When the housing H is pivoted, as described in the last preceding paragraph, the lower longitudinal edge thereof bears against the end of the elongated screw 48a of the block-like lever 48, as shown in Fig. 2, causing said lever 48 to turn

5 against the tension of spring 51, until the retaining arm 47 is brought out of contact with the groove 37a of outer bevel gear hub 37. The block-like lever 48 may also be turned independently of the housing H. Said lever 48 has a screw or other projection 111 on the upper surface thereof adjacent its free end, which is vertically aligned with the rod 54. When the transverse bar 52 is moved downwardly, as shown in 10 Fig. 4, the bottom end of the depending vertical rod 54 strikes this projection 111 to cause retaining arm 47 to be moved out of contact with the hub 37 of outer bevel gear 35.

15 As shown in Fig. 1, the rear end of the transverse bar 52 has a depending pin 112 which holds the top end of a vertical compression spring 113. The lower end of said compression spring 113 is seated in a vertical bore 114 of the machine frame. The spring 113 normally maintains bar 20 52 in an upward position.

The rack 41 has a transverse screw 115 fixed to the upper end thereof. When the rack is brought to its bottommost position of Fig. 4, said screw 115 strikes the top of transverse bar 52, 25 causing said bar 52 to move downwardly against the tension of compression spring 113.

30 The grinder bracket 58 has an upper extension 58a to which an upstanding pin 116 is fixed. The actuating lever 100 has a transverse extension-lug 117 which is vertically aligned with said pin 116 when said lever 100 is in its forward position of Fig. 6. When the grinder bracket 58 is brought to its uppermost position, as shown in Fig. 8, the pin 116 contacts the extension-lug 117 35 of actuating lever 100 and pivots said lever 100 upwardly. This pivoting of lever 100 causes the worm wheel 30 to disengage with worm gear 29, so that the grinder actuating mechanism of the machine is in its inoperative position and the grinder bracket 58 is held in its inoperative uppermost position.

35 When the grinder bracket 58 is to be brought into operative position from its uppermost position, the crank 100 is manually pivoted outwardly to the position shown in broken line in Fig. 6, in which position the extension-lug 117 can clear the pin 116 of said bracket 58. The crank 100 may then be pivoted downwardly past the extension-lug 117, causing the wheel 30 to engage with the worm gear 29.

40 The machine is provided with means for releasably holding the presser-foot rod 18 in its vertically adjusted position, means for releasing said presser-foot rod 18 when the lever 100 is pivoted downwardly, and means for releasing said presser-foot rod 18 independently of the grinder actuating mechanism. These means are clearly shown in Figs. 6, 7 and 8. The frame of the machine is provided with an extension 118, 45 at the rear thereof, said extension 118 containing a through-and-through longitudinal bore 119. As shown in Fig. 6 said bore 119 has a rectangular cross-section which conforms in shape to the cross section of presser-foot rod 18. Presser-foot rod 18 extends through said bore 119 and is vertically or longitudinally slidable therein. A transverse bore 120 extends through the side of 50 said frame extension 118 and communicates at its inner end with the longitudinal bore 119. The outer end of said transverse bore 120 opens 55 into an enlarged well 120a in the side wall of extension 118.

55 A plunger 121 is transversely slidable in the transverse bore 120, said plunger 121 having a tapered edge 121a which faces the vertical row

of teeth 19 of presser-foot rod 18. This tapered edge 121a is positioned to mesh with said teeth 19 when the plunger 121 is moved through the transverse bore 120 into contact with the presser-foot rod 18, thereby locking said presser-foot rod 18 in a vertically-adjusted position. A compression spring 122 urges the tapered edge 121a of plunger 121 out of contact with the teeth of presser-foot rod 18. The outer end of plunger 121 has an enlarged head 123 which is sized to slide transversely within the enlarged well 120a. As shown in Figs. 7 and 8, this head 123 has a cam-shaped outer face 123a.

A lateral shaft 124 is turnably mounted in a lateral bearing 125 of the machine frame, as shown in Fig. 6. This shaft is provided with a crank handle 124a. A block 126 is eccentrically mounted on the end of said lateral shaft 124. The cam face 123a of plunger head 123 is held in abutment with the end of said block 126 by the tension of compression spring 122.

The free end of block 126 is connected by a coil spring 121 to the block 99. When lever 100 and its attached block 99 are pivoted upwardly, as shown in Fig. 8, the tension of coil spring 121 is increased, causing the block 126 to pivot upwardly so that its inner edge bears against the cam face 123a of plunger head 123, causing the plunger 121 to move inwardly through transverse bore 120, against the tension of spring 122, until its tapered edge 121a meshes with the teeth of presser-foot rod 18.

When lever 100 is pivoted downwardly, its transverse extension lug 117 strikes the free end of block 126, as shown in Fig. 7, causing said block 126 to pivot downwardly to a position in which it no longer presses against the cam face 123a of plunger head 123. This releases the plunger 121 which is urged by compression spring 122 to a position in which it no longer meshes with the teeth of presser-foot rod 18, and said presser-foot rod 18 can be manually adjusted.

Pivoting of the crank handle 124a of lever 124 in a clockwise direction, also releases the presser-foot rod 18 for adjustment, independently of the actuating mechanism of the grinders. When the crank handle 124a is turned, it causes block 126 to pivot downwardly to a position in which the plunger 121 can be urged out of contact with the teeth of presser-foot rod 18. The presser-foot rod 18 may then be manually adjusted at any desired vertical position, and the crank handle 124a released. A lateral pin 128 is fixed to the frame of the machine below block 126, as shown in Fig. 7. Said pin 128 acts as stop means to prevent said block 126 from being pivoted downwardly through such a large angle that its end is moved out of contact with the cam face 123a of plunger head 123.

As shown in Fig. 9, one arm of a U-shaped lug 129 is secured to the bottom of the lower slide 66 preferably by means of screws 130. The unattached arm of said U-shaped lug 129 is held spaced from said lower slide 66, and in a position in which its terminal edge can contact the lateral projection 88 of presser-foot rod 18. As shown in Fig. 7, this lateral projection 88 has a hook-like lower portion 88a. When the grinder bracket 58 is lowered to its bottommost position, the presser-foot rod has already fallen to its bottommost position shown in Fig. 1, in which the presser foot 16 is resting upon the base 10 of the machine. As the grinder bracket approaches its bottommost position, the unat-

tached arm of the U-shaped lug 129 strikes the top of the hook-like lower portion 88a of lateral projection 88 and due to the resiliency of lug 129, said unattached arm bends upwardly and snaps over said hook-like lower portion 88a. The unattached arm of the U-shaped lug 129 is then located under said hook 88a, so that it may contact said bottom of said hook 88a when said grinder bracket 58 is raised, thereby simultaneously raising the presser-foot rod 18.

Operation

While the machine is used for cutting cloth, the rack 41 and grinder bracket 58 are held in their top positions of Fig. 2 with the housing H held in the non-operating position of Fig. 2. In this position of housing H, worm wheel 30 is out of mesh with worm gear 29, and retaining arm 47 is out of contact with the hub 37 of outer bevel gear 35. In this top position of grinder bracket 58, the extension arm 80a of control cam 80 abuts the screw head 89 in the bottom of the machine frame, so that the tapered bottom part of cam 80 holds the grinders 67 and 68 transversely spaced from the transverse faces of the edge of knife 15. The knife 15 can thus be reciprocated without sharpening the knife.

In this inoperative position of the grinders, the upstanding pin 116 of the grinder bracket 58 holds the actuating lever 100 in its upwardly-turned position of Fig. 8, in which the plunger 121 locks the presser-foot rod 18 in its vertical position. The presser-foot rod is set in a desired vertical position in which presser foot 16 is pressing down upon the pile of cloth being cut.

As shown in Fig. 2, the lateral screw 96 at the lower end of rack 41 is located within the rectangular slot 95 of the latch 91. The latch 91 is held in an immovable position by the projection of housing H adjacent the recess 90, which bears against the top of latch 91. The rack 41 and grinder bracket 58 are thus locked in their top position.

When it is desired to sharpen knife 15, the machine is moved by its handle 11 until the knife 15 is out of the pile of cloth. The actuating lever 100 is then pivoted rearwardly from its full-line position to its broken-line position of Fig. 6, in which the transverse extension-lug 117 is horizontally spaced from the upstanding pin 116 of grinder bracket 58. The actuating lever 100 is then pivoted downwardly to the position of Fig. 7 by the tension of spring 127. The block 99 also pivots downwardly with the lever 100, and the bottom of said block 99 strikes the free end of block 126, causing said block 126 to pivot until it abuts the stop pin 128. In this position the block 126 eases its inward pressure upon cam-face 123a of plunger 121, enabling said plunger 121 to be urged outwardly by compression spring 122 until its tapered end 121a is no longer in latched engagement with the teeth of presser-foot rod 18. Said presser-foot rod 18 thereupon descends under the force of gravity to its lower position of Fig. 1, in which the presser foot 16 abuts the top of base 10.

Lowering of the actuating lever 100 is accelerated by the torsion spring 105. As said actuating lever 100 pivots downwardly, it causes the lever 98 to turn from its position of Fig. 2, to its position of Fig. 3 in which its bottom end strikes the head of pin 107 and turns the housing H to its operative position of Fig. 3 in which worm wheel 30 is in mesh with worm gear 29. In this posi-

11

tion the latch-finger 94 of latch 91 enters the recess 90 of housing H, locking housing H in its operative position. In this position, the rectangular slot 95 is moved clear of the lateral screw 96 of rack 41, so that rack 41 is free to move downwardly. As housing H moves to its operative position it disengages from the end of the enlarged screw 48a of the block-like lever 48, causing said lever 48 to be pivoted upwardly by spring 51 until the retaining arm 47 is in the vertical position of Fig. 3. The horizontal shaft 39 is held in its outer position by compression spring 43, as shown in Fig. 6, in which position the inner bevel gear 36 is in mesh with the bevel gear 34, and the hub 37 of outer bevel gear 35 is held in a position in which its groove 37a is in alinement with said retaining arm 47. When the retaining arm 47 is brought to its vertical position of Fig. 3, its arcuate groove enters groove 37a of hub 37, and thereby locks the inner bevel gear 36 in its meshed relation with bevel gear 34. As the motor within casing 12 operates, it rotates the disc 25 whose peripheral worm gear 29 turns worm wheel 30 in a clockwise direction. The pinion 40 is rotated in such a direction that the rack 41 is lowered. The grinder bracket 58 is thus driven downwardly by the motor housed within casing 12. Fig. 1 shows the bracket 58 in an intermediate position during its downward travel. During the downward movement of the grinder bracket 58, the grinders 67 and 68 are transversely spaced from each other and from the edges of the knife 15 since the pin 78 is located within the arcuate recess 80d of control cam 80, holding said control cam 80 in its downwardly-pivoted position.

If for any reason, the presser-foot rod 18 should become stuck and fail to reach its bottom position of Fig. 1, on the downward movement of the bracket 58, the end of U-shaped lug 129 will strike the lateral projection 88 of presser-foot rod 18, and carry said presser-foot rod 18 to its bottom position.

Close to its bottom position, the extension arm 80a of control cam 80 strikes the top surface of lateral projection 88 of presser foot rod 18, turning said control cam 80 upwardly to a non-operating or release position shown in Fig. 5, so that the grinders 67 and 68 are moved transversely toward each other to contact with the opposed edge faces of knife 15.

Simultaneously, the free end of the resilient U-shaped lug 129 snaps past the hook-line lower end 88a of lateral projection 88, and takes a position below said lateral projection 88, as shown in Fig. 7. Since the U-shaped lug 129 is fixed to the lower slide, when the grinders 67 and 68 are moved toward each other, the free end of U-shaped lug 129 is moved transversely inward beneath lateral projection 88 to a position in which it can engage the lower surface of lateral projection 88 and raise the presser-foot rod 18 when the bracket 58 is raised.

Simultaneously with the raising of control cam 80 to its release position, the upper lateral screw 115 on the rack 41 carries the transverse bar 52 downwardly to its bottom position of Fig. 4 in which the bottom of its depending vertical rod 54 contacts the screw 111 of block-like lever 48 and turns said lever 48 downwardly. This moves the retaining arm 47 out of contact with the hub 37 of outer bevel gear 35. As the transverse bar 52 is lowered, its attached flat spring 55 is moved downwardly so that its cam-shaped bottom end 57 rides over the outer face of the hub 37 of outer

12

bevel gear 35. The resilient flat spring 55 pushes the horizontal shaft 39 inwardly so that the inner bevel gear 36 disengages from bevel gear 34 and the outer bevel gear 35 engages with bevel gear 34. This causes the pinion 40 to reverse its direction of rotation and to turn in a direction to raise rack 41.

As the rack 41 and bracket 58 begin their upward movement, as shown in Fig. 5, the upper lateral pin 115 is raised, allowing the transverse bar 52 to be urged upwardly by compression spring 113. Transverse bar 52 carries its depending vertical rod 54 upwardly and out of contact with the screw 111 of the block-like lever 48. The lever 48 is then turned by the tension of spring 51 to its position of Fig. 5, in which the upper end of retaining arm 47 abuts the front face of hub 37. The outer bevel gear 35 is thus locked in its engaged position with bevel gear 34. When the transverse bar 52 reaches its top position, the cam end 57 of flat spring 55 is raised out of contact with the face of hub 37 as shown in Fig. 5.

The pinion 40 now slowly raises rack 41 and grinder bracket 58 to their top position, while the turnable grinders 67 and 68 are turned under suitable friction around their respective shafts which are connected to bracket 58, thus sharpening the knife 15 only during the upward movement of said grinders 67 and 68. The knife 15 is reciprocated during the upward movement of grinders 67 and 68. The presser-foot rod 18 is carried upward with bracket 48 by the engagement of U-shaped lug 129 with the bottom of lateral projection 88.

Close to the end of the upward grinding movement of bracket 58 and rack 41, the extension arm 80a of control cam 80 strikes the screw head 89 in the machine frame, thus turning cam 80 to its position of Fig. 2 in which the grinders 67 and 68 are in their separated and inoperative positions. Also, the upstanding pin 116 contacts the actuating lever 100 and pivots said lever 100 upwardly to its position of Fig. 8. At the same time, the lower lateral screw 96 of rack 41 enters the rectangular slot 95 in the latch 91 and abuts the top edge of said slot 95, causing the rear end of the latch 91 to pivot upwardly and causing the latch finger 94 to leave the recess 90 of housing H. Since housing H is now released, raising of the actuating lever 100 causes said housing H to turn to its inoperative position of Fig. 2 in which the worm wheel 30 is out of mesh with the worm gear 29.

As housing H turns, it carries with it block-like lever 48 so that the retaining arm 47 moves out of contact with hub 37 of outer bevel gear 35. The horizontal shaft 39 is thus released, and is urged forwardly by compression spring 43, until the inner bevel gear 36 engages the bevel gear 34.

The grinding mechanism has thus been returned to its original inoperative position of Fig. 2, in which position it is held until it is again necessary to sharpen the knife. Ordinarily, a single downward and upward movement of the grinders relative to the frame of the machine is sufficient to sharpen the knife. It is to be noted that the entire grinding operation was automatically effectuated upon a single manual stroke of the actuating lever 100.

In the upward movement of the grinder bracket 58 and rack 41, the bracket 58 carries the presser-foot rod 18 to its top position. As bracket 58 approaches its top position, actuating arm 100 is turned upwardly by pin 116, causing block 126

to pivot upwardly and force plunger 121 into latched engagement with the teeth of presser-foot rod 18. This latching of presser-foot rod 18 occurs shortly before grinder bracket 58 reaches its top position. Grinder bracket 58 therefore continues to move upwardly a short distance relative to the presser-foot rod 18 which is locked in its uppermost position, causing the end of the resilient U-shaped lug 129 to be raised past the hook-like lower end 88a of lateral projection 88.

When the grinder bracket 58 thus reaches its uppermost position, the hook-like lower end 88a of lateral projection 88 is located beneath the end of U-shaped lug 129, and in a position to be released free of the grinder bracket 58.

The presser-foot rod 18 may then be released by turning the crank handle 124a, while the grinding mechanism remains in its inoperative position, and the presser-foot rod may be manually set in its suitable vertical position.

I have shown a preferred embodiment of my invention, but it is clear that numerous changes and omissions can be made without departing from its spirit and scope. For convenience, I have described the device in the position in which the knife reciprocates in a vertical path, but of course the machine could be held in any suitable position.

I claim:

1. In a cloth cutting machine having a fixed frame, a knife mounted to reciprocate vertically relative to said frame, and a motor; a knife sharpening device comprising a rack mounted for vertical movement in said frame, a grinder carriage mounted on the lower end of said rack and carrying grinder means for sharpening said knife, a gear train connecting said motor to said rack for driving said rack vertically between an uppermost position in which said grinder carriage is adjacent the top of said knife and a lowermost position in which the grinder carriage is adjacent the bottom of said knife, said gear train including first and second intermediate gear means movably mounted for successive and alternate meshing engagement with said gear train, said first intermediate gear means being arranged to drive said gear train in a direction to lower said rack, said second intermediate gear means being arranged to drive said gear train in a direction to raise said rack, means carried by said rack for bringing said first intermediate gear means into meshing engagement with said gear train when said rack is in its uppermost position, and means carried by said rack for bringing said second intermediate gear means into meshing engagement with said gear train when said rack is in its lowermost position.

2. In a cloth cutting machine having a fixed frame, a knife mounted to reciprocate vertically relative to said frame, and a motor; a knife sharpening device comprising a rack mounted for vertical movement in said frame, a grinder carriage mounted on the lower end of said rack and carrying grinder means for sharpening said knife, a gear train connecting said motor to said rack for driving said rack vertically between an uppermost position in which said grinder carriage is adjacent the top of said knife and a lowermost position in which the grinder carriage is adjacent the bottom of said knife, said gear train including first and second intermediate gear means movably mounted for successive and alternate meshing engagement with said gear train, said first intermediate gear means being arranged to drive said gear train in a direction to

lower said rack, said second intermediate gear means being arranged to drive said gear train in a direction to raise said rack, means carried by said rack for bringing said first intermediate gear means into meshing engagement with said gear train when said rack is in its uppermost position, means carried by said rack for bringing said second intermediate gear means into meshing engagement with said gear train when said rack is in its lowermost position, said gear train being movably mounted on said frame for movement between an operative position in which it engages said motor and an inoperative position in which it is disengaged from said motor, means on said frame positioned for manual actuation to move said gear train to its operative position, and means carried by said rack for moving said gear train to its inoperative position when said rack reaches its uppermost position.

20 3. In a cloth cutting machine having a fixed frame, a knife mounted to reciprocate vertically relative to said frame, and a motor; a knife sharpening device comprising a rack mounted for vertical movement in said frame, a grinder carriage mounted on the lower end of said rack and carrying grinder means for sharpening said knife, a housing pivotally mounted on said frame, a gear train mounted in said housing and connecting said rack to said motor, said gear train including a drive gear located to mesh with said motor, a drive bevel gear coupled to said drive gear and turnable in unison therewith, a first and second intermediate bevel gear mounted face to face on a common shaft on either side of said drive bevel gear for meshing relationship therewith, said shaft being slidable in said housing between a first position in which only the first intermediate bevel gear is in mesh with the drive bevel gear, and a second position in which said second intermediate bevel gear is in mesh with said drive bevel gear, said shaft being also coupled to a pinion in constant mesh with said rack, said first and second intermediate bevel gears being adapted to respectively raise and lower said rack, spring means normally biasing said shaft to its first position, cam means actuatable by said rack to slide said shaft to its second position when said rack reaches its lowermost position, said housing being pivotable between an operative position in which said drive gear is in mesh with the motor and an inoperative position in which the drive gear is out of mesh with said motor, an operating handle mounted in said frame and coupled to said housing for pivoting thereof, said rack carrying a fixed member positioned to contact said handle and raise said handle to a position in which it pivots said housing to its inoperative position when said rack is raised to its uppermost position, said handle being also positioned for manual movement to a release position in which it is clear of said fixed member and free for movement to a depressed position in which said housing is pivoted to its operative position.

4. A knife sharpening device according to claim 3 in which said grinder means comprises a pair of horizontally-slidable bars mounted on said grinder carriage, a grinder stone mounted on each of said bars, spring means urging said bars in opposite directions to bring said grinder stones in contact with said knife, a pin mounted on each said bar, and a wedge shaped spreader pivotally mounted on said grinder carriage for movement between said pins, said spreader being of sufficient width to force said pins apart a sufficient distance to space said grinder stones out of con-

tact with said knife, said machine frame having a fixed portion positioned to contact said spreader and pivot said spreader between said pins when the rack reaches its uppermost position, said machine having a projection rigid therewith and positioned to contact and pivot said spreader out of contact with said pins when said rack reaches its lowermost position.

5. A sharpening device according to claim 4 in which said machine also has a presser foot rod carrying a presser foot and mounted for vertical longitudinal movement in said frame between an uppermost position in which the presser foot is adjacent the top of said knife and a lowermost position in which the presser foot is adjacent the bottom of said knife, said frame carrying manually-releasable locking means for holding said presser-foot rod in a selected adjusted vertical position intermediate its uppermost and lowermost positions, said operating handle being operatively coupled to said locking means for release thereof when said handle is brought to its depressed position, whereby said presser foot rod is free to drop to its lowermost position, said presser foot rod having a lateral projection adjacent its lower end, one bar of said grinder carriage bearing a lateral detent positioned to engage said lateral projection when grinder stones are moved into contact with said knife, whereby said grinder carriage raises said presser foot rod when the rack is raised, said presser foot rod also carrying the projection for pivoting the spreader out of contact with the pins.

6. In combination with a cutting machine having a frame, a motor, and a knife mounted for vertical reciprocation in said frame and having a cutting edge; a sharpening device mounted in said frame for movement in a direction substantially parallel to the cutting edge of said knife between an uppermost position in which said sharpening device is adjacent the top of said knife, and a lowermost position in which said sharpening device is adjacent the bottom of said knife, a presser foot rod mounted in said frame for movement in a direction substantially parallel to the edge of said knife between an uppermost position adjacent the top of said knife and a lowermost position adjacent the bottom of said knife, locking means to hold said presser foot in a selected adjusted position intermediate its uppermost and lowermost positions, locking means to hold said sharpening device in its uppermost position, driving means driven by said motor and coupled to said sharpening device for moving said sharpening device through a downward and upward cycle from its uppermost to its lowermost position and back to its uppermost position, man-

ually operable means to actuate said driving means and simultaneously to release the locking means from said presser foot rod whereby said presser foot rod is free to fall to its lowermost position, said presser foot rod having a lateral projection, detent means on said sharpening device positioned to engage and hold said projection at the lowermost position of said sharpening device and presser foot rod, said sharpening device carrying said presser foot rod to its uppermost position by means of said detent, means associated with said machine frame and positioned to contact said presser foot rod to move said presser foot rod out of engagement with said sharpening device when said sharpening device and presser foot rod reach their uppermost position.

7. A device according to claim 6 in which said sharpening device has sharpening means, spring means to hold said sharpening means in contact with said knife during the upward movement of said sharpening device, and means for automatically bringing said sharpening means out of contact with said knife when the sharpening device is in its uppermost position, and for holding said sharpening means out of contact with the knife during the downward movement of said sharpening device.

8. A device according to claim 7 in which said spring means are connected to a manually-adjustable member adapted to be set and retained at selected positions to vary the tension of said spring means.

9. A device according to claim 7 in which said sharpening device has manually-adjustable screw means for moving said sharpening means perpendicularly of the longitudinal edge of said knife.
